UNITED STATES PATENT OFFICE.

WILLIAM C. ANDERSON, OF TOLEDO, OHIO, ASSIGNOR TO THE LIBBY GLASS COMPANY, OF SAME PLACE.

DESIGN FOR ORNAMENTATION OF GLASSWARE.

SPECIFICATION forming part of Design No. 22,213, dated February 14, 1893.

Application filed November 19, 1892. Serial No. 452,589. Term of patent 3½ years.

To all whom it may concern:

Be it known that I, WILLIAM C. ANDERSON, of Toledo, in the county of Lucas and State of Ohio, have invented a new and original Design for the Ornamentation of Glassware, of which the following is a specification.

The class to which this design relates is that of ornamentation of glassware, and the design pertains to the ornamentation of the exterior surface thereof.

The drawings represent, in Figure 1, a bottom plan view of a dish containing the design, and in Fig. 2 a transverse section on lines *x x*, Fig. 1.

The design is applicable to any kind of glassware, such as bowls, plates, jugs, and dishes.

The leading features of my design are the large central stellated figure *a* and the circular series or row of smaller stellated figures *b* arranged outside of said central figure. The central figure *a* is composed of a series of substantially elliptic rays 22 each composed of curved bars or stripes and all radiating from an ornamented center 3. Said rays are re-

lieved by the net work ornamentation in the 25 adjacent spaces. Each ray terminates at its outer end in a single acute angle or point. As here shown the dish has a handle *c* which however is not an essential feature of my design.

I claim—

The design for the ornamentation of glassware herein described and shown, the same consisting of the central stellated figure having substantially elliptical rays, each terminating in a single acute angle or point at its outer end, and the series of smaller stellated figures outside of said central figure, as set forth.

In testimony whereof I have signed my 40 name to this specification, in the presence of two subscribing witnesses, this 10th day of November, A. D. 1892.

WILLIAM C. ANDERSON.
